Primary Examiner — Mark Goodwin

(74) Attorney, Agent, or Firm — Robert C. Montgomery;
Montgomery Patent and Design LLC(57) **CLAIM**

The ornamental design for a post pulling device, as shown and described.

DESCRIPTION

FIG. 1 is a front perspective view of a post pulling device, showing my new design;
FIG. 2 is a rear perspective view thereof;
FIG. 3 is a front elevation view thereof;
FIG. 4 is a rear elevation view thereof;
FIG. 5 is a left side elevation view thereof, wherein a right side elevation view is a mirror image thereof;
FIG. 6 is a top plan view; and,
FIG. 7 is a bottom plan view thereof.

1 Claim, 6 Drawing Sheets(56)
